UNITED STATES PATENT OFFICE.

ERNEST CLEFF, OF FAIRHAVEN, MASSACHUSETTS, ASSIGNOR TO THE PAIRPOINT MANUFACTURING COMPANY, OF NEW BEDFORD, MASSACHUSETTS.

DESIGN FOR A CASKET-HANDLE EAR.

SPECIFICATION forming part of Design No. 25,307, dated March 31, 1896.

Application filed February 28, 1896. Serial No. 581,209. Term of patent 7 years.

To all whom it may concern:

Be it known that I, ERNEST CLEFF, of Fairhaven, in the county of Bristol and State of Massachusetts, have invented a new Design for Casket-Handle Ears, of which the following is a specification.

Referring to the accompanying drawings, Figure 1 is a plan view, Fig. 2 a side elevation, and Fig. 3 an end elevation, of a casket-handle ear containing my design, these three views being deemed necessary to fully illustrate my new design.

The leading feature of my design consists in a raised marginal knurl, which is flanked at two opposite sides by corner-forming scrolls, which are inclined, as a whole, from the sides of the knurl to the ends of the ear; the knurl descending toward the opposite margin of the ear to about the middle thereof, and there terminating in a point inclosed with radial groovework on a flattish field extending to the slightly-raised side margin of scrollwork opposite the knurl and corner-scrolls.

A is the high marginal knurl ornamented with leafwork a , and extending downwardly to a point a' near the middle of the ear. Point a' is inclosed in radiating groovework a^2 , which is surrounded, except on the knurl side, by a flattish field a^3 , the outer ends of grooves a^2 being inclosed by a series of round-point plain-faced loopwork a^4 . Knurl A is flanked at opposite sides by bold corner-scrolls B, beginning at b , near the opposite corners and

terminating in bosses b' . Each scroll B, taken as a whole, is inclined downwardly from the 35 knurl to the end margins of the ear, which, viewed in top-plan, is approximately parallelogrammatic in outline. Short scrolls b^2 spring from the corner-scrolls B. The depressed portions of each scroll B are ornamented with pendent drops b^3 . One long edge of the ear, along the margin opposite the knurl, has a raised rib D terminating in scrolls d . Sockets F occupy the two corners opposite the corners occupied by the corner-scrolls B, the contiguous corners of the plate having angular projections f and bosses f' at end of inward edge curves f^2 , which turn inwardly at f^3 , making recesses thereat on the edge of the plate. The edge of the ear is 50 plain-surfaced, but indented at g , g' , g^2 , g^3 , g^4 , and g^5 along its rear edge, which, viewed in rear elevation, shows the knurl at the middle and the adjacent corner-scrolls descending to opposite ends of the ear. 55

What I claim is—

The design for a casket-handle ear herein shown and described.

In testimony whereof I have signed my name to this specification, in the presence of 60 two subscribing witnesses, on this 15th day of February, A. D. 1896.

ERNEST CLEFF.
